Primary Examiner — Michael A Pratt

(57) **CLAIM**

The ornamental design for a compound bow cam, as shown and described.

DESCRIPTION

FIG. 1 is an angled isometric top view of the compound bow cam.

FIG. 2 is an angled isometric bottom view of the compound bow cam.

FIG. 3 is a top view of the compound bow cam.

FIG. 4 is a bottom view of the compound bow cam.

FIG. 5 is a front view of the compound bow cam.

FIG. 6 is a back view of the compound bow cam.

FIG. 7 is a right side view of the compound bow cam; and, FIG. 8 is a left side view of the compound bow cam.

1 Claim, 4 Drawing Sheets
